UNITED STATES PATENT OFFICE.

HARRY A. SEARLE, OF COUNCIL BLUFFS, IOWA.

GREASE-DRUM.

1,328,768.

Specification of Letters Patent. Patented Jan. 20, 1920.

Application filed February 4, 1919. Serial No. 274,919.

To all whom it may concern:

Be it known that I, HARRY A. SEARLE, a citizen of the United States, residing at Council Bluffs, in the county of Pottawattamie and State of Iowa, have invented a certain new and useful Improvement in Grease-Drums, of which the following is a specification.

The invention relates to drums or containers in which transmission greases and like lubricants are transported, and the object of the invention is to provide a shipping package of this character with an inclosed pump permanently attached, by which the contents of the drum may be easily delivered as required, as for example, to the gear-case or other portion of a motor-vehicle mechanism, and which shall be economical in construction and operation, and capable of withstanding the rough handling to which containers of this class are subjected in transportation, without danger of damage to the contained pumping mechanism.

The invention consists in certain novel features and details of construction and arrangement by which the above objects are attained, to be hereinafter described and claimed.

The accompanying drawings form a part of this specification and show the invention as it has been carried out in practice.

Figure 1 is a front elevation of the drum with a portion of the shell broken away to show the contained pump. Fig. 2 is a vertical section taken on the line 2--2 in Fig. 1, and partly in elevation. Fig. 3 is a horizontal section taken on the line 3--3 in Fig. 2, and partly in plan view.

Similar letters of reference indicate the same parts in all the figures.

A is the cylindrical shell or body of the drum, of the usual heavy sheet steel, having a closed bottom A¹, and flanged top A² adapted to receive a circular friction cover A³ held in place and tightly closed by bolts A⁴ and serving as a closure for the large circular filling opening in the top.

B is a bar extending on a chord across the interior of the drum a short distance above the bottom A¹ and bolted at its ends to the inwardly projecting flanges of two vertical angle-irons B¹ welded or otherwise secured on the interior of the drum. The bar serves as a support for a rotary pump C of any approved type bolted thereto with

its suction orifice located as low as practicable so as to draw upon the heavy grease near the bottom of the drum and to permit, as nearly as possible the complete emptying of the drum.

On the shaft C¹ of the pump is mounted a sprocket-wheel C² on which is engaged a sprocket-chain D extending upwardly and running over a smaller sprocket-wheel E¹ on a driving-shaft E extending diametrically across the drum above the pump and parallel with the pump-shaft C¹. The pump is operated by turning the shaft E.

One end of the shaft E is received in a bearing F on the interior of the drum and the other end in a boss G extending through the wall of the drum and shown as secured on the exterior by a flange G¹. The inner end of the boss G is provided with a stuffing-box G² through which the driving-shaft passes, and the end of the shaft is squared and is presented within a screw-threaded opening or recess g in the boss. By inserting the socket of a crank H into the opening g, the shaft E is engaged and turned and the pump operated. The opening g is provided with a screw-plug, not shown, by which it is tightly closed in transportation.

C² is the delivery pipe of the pump, extending vertically from the upper portion thereof and thence horizontally on a radial line to a boss J projecting into the interior of the drum and having a flange J¹ by which it is secured to the exterior of the drum, similar to the boss G above described, and having a screw-threaded orifice, preferably of the same size and thread as the recess g, receiving a screw-plug, not shown, by which the boss J may be effectually closed. By making the openings in bosses similar, the screw-plugs may be used interchangeably, as will be understood.

The orifice on the exterior of the drum, in the boss J, is also adapted to receive a coupling M¹ of a delivery hose M equipped with a valved nozzle M² through which the grease or other lubricant is delivered from the pump.

N is a wheeled truck adapted to carry the drum and permit it to be easily moved about on the floor of the garage as required.

In supplying the lubricant the screw-plugs, not shown, are removed, the hose attached to the boss J, and the crank H inserted in the boss G and engaged with the shaft E; the nozzle M² is presented at the

desired point in the motor mechanism and the crank turned until the desired quantity is discharged.

When the drum has been emptied the hose 5 is disconnected and the crank removed, the plugs are inserted and the drum is ready to be re-shipped for re-filling.

It will be noted that any handling of the grease is avoided and a corresponding saving in waste is effected.

The bar B on which the pump is mounted serves as a transverse brace to stiffen the drum, and the pump thus suspended, out of contact with the wall and bottom of the drum, is protected against direct impact from neighboring packages, or other objects during transportation and handling. The drum may receive the usual rough treatment to which containers of this character are exposed without danger of damage to the pumping mechanism.

I claim:—

1. The container described, consisting of a drum, a pump suspended within said drum and supported solely by the side-walls of the drum out of contact with the walls and bottom thereof, means for operating said pump from the exterior of said drum, and a delivery pipe from said pump to the exterior 30 of said drum.

2. The container described, consisting of a drum having a bar extending across its interior, a pump mounted on and supported solely by said bar out of contact with said drum, means for driving said pump, and a delivery pipe from said pump to the exterior of said drum.

3. The container described, consisting of a drum having a bar extending across its interior and secured to its wall, a pump mounted on and supported solely by said bar out of contact with said drum, and having a pump-shaft, a sprocket-wheel on said pump-shaft, a driving-shaft on the interior of said

drum above and parallel with said pump-shaft, a sprocket-wheel on said driving-shaft, a sprocket-chain running on said wheels, means on the exterior of said drum for turning said driving-shaft, and a delivery pipe leading from said pump to the exterior of said drum.

4. The container described, consisting of a drum, a pump suspended therein above the bottom thereof and supported solely by the side-walls of the drum out of contact with its walls, a delivery pipe leading from said pump to a delivery orifice on the exterior of said drum, and means for operating said pump, said orifice being adapted to receive a delivery hose or a closing plug.

5. The container described, consisting of a drum, a pump suspended therein above the bottom thereof and supported solely by the side-walls of the drum out of contact with its walls, a delivery pipe leading from said pump to the exterior of said drum, a driving-shaft within said drum above said pump, a sprocket-wheel on said pump, a sprocket-wheel on said driving-shaft, and a sprocket-chain on said wheels, one end of said driving-shaft projecting into a recess on the exterior of said drum, such recess adapted to receive a crank for turning said shaft, or a plug for closing such recess.

6. A container comprising a shell, a transverse member therein secured to the opposite walls above the bottom and transversely bracing said shell, and a pump suspended and supported solely by said member entirely out of contact with the bottom and walls of said shell.

In testimony that I claim the invention above set forth I affix my signature in presence of two witnesses.

HARRY A. SEARLE.
